AMPLIFIER SYSTEM

Allan K. Ross, Rochester, N. Y.

Application April 25, 1925. Serial No. 25,780

5 Claims. (Cl. 250—40)

This invention relates to amplifier systems and in particular to amplifier systems for use in amplifying radio signals.

In certain types of amplifier systems it has been customary to employ a plurality of tuned amplifying stages. Such an arrangement, while it gives excellent results, is expensive to manufacture since it requires a variable condenser for each stage with the result that there are at least 10 as many controls as there are amplifying stages. In order to overcome the objection of a plurality of controls in such a multistage amplifying system it has been proposed to mount all of the condensers on a common shaft or else 15 to gear the rotors of the condensers so that they may be actuated by a common control. Such an arrangement, however, has proved to be impracticable because it is impossible to make each of the stages with the same electrical constants so that while it is possible to tune the stages 20 to the same frequency over a very limited range, over a wide portion of the range of frequencies the stages are not in resonance so that accurate tuning does not take place. In order to overcome 25 this difficulty it has been proposed to provide one master control for roughly tuning each of a plurality of stages, and further to provide an individual vernier control for the accurate tuning of each stage. The necessity for such a vernier control defeats the purpose of such a master control arrangement.

In accordance with the present invention it is proposed to obviate the necessity of providing a variable condenser and an individual control 35 therefor in each amplifying stage and to avoid the undesirable features of the master controlled system by providing a single variable capacity common to a plurality of amplifying stages whereby all of the stages may be simultaneously 40 and accurately tuned by the use of a single control.

The drawing represents the invention applied to a tuned radio frequency amplifying radio receiver, although it will be understood that it may be used with audio amplifying systems or in any other arrangement wherein a plurality of stages are tuned to the same or to an approximately 45 equal degree of resonance.

To the left of the drawing there is represented 50 an antenna 5 connected to ground through the primary winding 6 of a radio frequency transformer. The secondary winding 7 is connected in the input circuit of a thermionic device or vacuum tube 8. This input circuit extends from 55 the grid 9 of this vacuum tube through the sec-

ondary winding 7, the potentiometer 10 to the filament 11. The fixed condenser 12 in series with the common variable condenser 13 is connected in multiple across the input circuit and the capacity of the fixed condenser 12 with that 60 of the variable condenser 13 and the inductance of the secondary coil 7 serve to tune the input circuit just described. The output circuit of the thermionic device 8 extends from the plate 14 thereof through the primary winding 15 of a second radio frequency transformer through the high potential B battery 16 and common conductor 17 to the filament system including the low voltage A battery 18 by which the filaments 65 of the various thermionic devices are heated. 70 The primary winding 15 as in the case of the first primary winding 6 is closely coupled to the secondary winding 19 which is connected in the input circuit of a second thermionic device 20 which functions as a second stage for amplifying 75 radio frequency currents. This input circuit may be traced from the grid 21 through the secondary winding 19 and through the potentiometer 10 to the filament system including the common conductor 17 and the filament 23. A fixed condenser 80 22 in series with the common variable condenser 13 is connected in multiple with the secondary winding 19 across the last mentioned input circuit. The output circuit of this last mentioned stage includes the plate 24, primary winding 26 85 of a third radio frequency transformer, conductor 25, the high voltage battery 16, the common conductor 17 to the filament 23. The primary winding 26 of this third mentioned transformer is closely coupled to the secondary winding 27 90 thereof which is included in the input circuit of a detector tube 28. This input circuit is likewise tuned by a fixed condenser 28 connected in series with the common variable condenser 13 across 95 the input circuit in multiple with the secondary winding 27. It will be noted that this input circuit includes the well known grid condenser 29 and the grid leak 30 to control the potentials present on the grid 31 of the detector. The filament 32 of the detector is heated from the battery 18 as in the case of the thermionic devices 8 and 20, but in this instance a variable rheostat 33 for controlling the heating of this tube is provided instead of the fixed resistance controls 34 100 and 35 of the other filaments. The output circuit of the detector tube as herein shown extends from the plate 36 to an indicating device 37 which may be in the form of telephone receivers or a 105 loud speaker. When these devices are used a 110

well known by-pass condenser 38 may be employed. It will be understood that the indicating device 37 and the by-pass condenser 38 may be replaced by the primary winding of an audio transformer the secondary winding of which is connected in the input circuit of an audio amplifying thermionic device.

From the foregoing it will be understood that the input circuits of the thermionic devices 8 and 20 and the detector tube 28 are all tuned to the frequency of the incoming signal by means of the common variable condenser 13 which is connected in series with the fixed condensers 12, 22, and 28. All of the mentioned fixed condensers are of the same capacity and the inductances of secondary windings 7, 19, and 27 are all equal, so that any change made in the capacity of the variable condenser 13 causes a corresponding change in the effective capacity connected across the mentioned windings which changes the tuning of each input circuit and insures that all circuits are tuned to the same frequency over the entire band of wave lengths covered by any combination of inductance and capacity.

It has been found in practice that such a set is especially easy to operate since it requires the adjustment of only one variable condenser and the possible adjustment of the potentiometer 10 in the event that there is any tendency for undesirable oscillations in the receiver.

While the invention has been disclosed as a radio frequency amplifier in a radio receiver, it will be understood that it may be employed for

either radio or audio frequency amplification, and may even be used in any other arrangement where it is desired to tune simultaneously and equally a plurality of stages.

What I claim is:

1. In a radio receiving apparatus, a plurality of stages, each including a thermionic device, means for simultaneously tuning said stages to a desired signal, said means including a fixed condenser connected in each stage, and a variable condenser common to said plurality of stages. 80

2. In a radio receiving apparatus, a plurality of stages, each including a thermionic device, an inductive reactance and a capacitive reactance connected in each stage, and a variable condenser in series with a plurality of said capacitive reactances for simultaneously tuning said stages. 85

3. The method of tuning a multi-stage thermionic amplifier having fixed inductive reactance and fixed capacitive reactance in each stage which consists in adding a variable reactance supplementing said fixed reactance. 90

4. The method of tuning a multi-stage amplifier having inductance and capacity in each stage which consists in supplementing the capacity in each stage by common variable capacity. 95

5. The method of tuning a multi-stage amplifier having inductance and capacity in a closed net-work in the input circuit of each stage which consists in supplementing the capacity in the closed net-work of each stage by common variable capacity. 100
